UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed December 5, 1927. Serial No. 237,933.

This invention relates to mining apparatus and more particularly, but not exclusively, to an adjustable wheeled support for a longwall mining machine.

An object of this invention is to provide an improved wheeled support for a mining apparatus. Another object of this invention is to provide an improved adjustable wheeled support for a mining machine whereby the 5 elevation and angle of the machine may be varied. Still another object is to provide an improved adjustable wheeled support for a mining machine whereby the latter may be rocked or tilted about longitudinal and transverse 10 axes. Yet another object is to provide an improved adjustable wheeled support for a mining machine especially adapted to use with a conveyor system operating at a longwall face, the wheeled support being so constructed as 15 to permit the machine to operate directly above the face conveyor with the latter located along the trackway between the supporting wheels. Yet another object is to provide an adjustable wheeled truck for a self-contained 20 longwall mining machine of the type normally slidable on its bottom on the mine bottom during the cutting operation, said truck being so constructed as to enable the machine to be adjusted about a longitudinal 25 axis and to enable the elevation and angle of the machine to be varied to suit different operating conditions. These and other objects and advantages of this invention will, 30 however, subsequently more fully appear.

In the accompanying drawings there is shown for purposes of illustration one embodiment which the invention may assume in practice.

In these drawings,—

Fig. 1 is a side elevational view of a self-contained longwall mining machine mounted on the improved adjustable wheeled support, the machine being shown in its lowered position.

Fig. 2 is a plan view of the apparatus shown in Fig. 1.

Fig. 3 is a rear elevation of the apparatus shown in Figs. 1 and 2, the machine being shown in operating position directly above 50 the face conveyor.

Fig. 4 is a detail sectional view taken on line 4—4 of Fig. 2.

Fig. 5 is a detail sectional view taken on line 5—5 of Fig. 4.

Fig. 6 is a detail sectional view taken on line 6—6 of Fig. 4.

Fig. 7 is a somewhat diagrammatic view illustrating the machine supported in its elevated position, the machine being shown 60 tilted as indicated by dotted lines.

Fig. 8 is a diagrammatic view illustrating the machine operating on a longwall face in a mine.

In accordance with this illustrative embodiment of the invention there is shown an adjustable wheeled truck frame 1 consisting of parallel longitudinally extending angle or frame members 2 connected in rigid spaced relation by transverse angle or frame members 3. Rigidly fixed to transverse horizontal shafts 4 journaled in brackets 5 rigidly secured to the angle members 2 are oppositely extending arms 6. These arms as clearly shown in Fig. 3 are bifurcated at 7 at their lower ends and these bifurcated ends carry axles 8 on which truck wheels 9 are journaled. These arms and truck wheels constitute the sole support for the machine. The ends 10 of the arms 6 at one side of the truck 65 extending oppositely from their respective shafts from the truck wheels are also bifurcated and are each pivotally connected at 11 to one of the ends of a pair of link members or arms 12. The other ends of link members 70 or arms 12 are pivotally connected at 13 to non-rotatable trunnions 14. These trunnions are in the form of nuts and have formed therein right and left hand threads respectively engaging the right and left hand 75

threads on a rotatable and slidable screw 15. This screw extends longitudinally of the apparatus at one side thereof as clearly shown in Figs. 1 and 2. This screw is mounted for 5 rotative and sliding movements intermediate its ends in an upstanding bracket or bearing member 16 suitably rigidly secured to one of the angle members 2. The rear end of the screw 15, as shown in Fig. 4, extends into a hollow rotatable shaft or sleeve 17 suitably rotatably mounted within thrust bearings 18 suitably carried within a casing 19 suitably rigidly fixed to the adjacent angle member 2. Threadedly connected at 10 20 within the rear end of the sleeve 17 is a pressure screw 21 having its forward end abutting the rear end of the screw 15 as at 22. It will also be noted that the screw 15 is splined at 23 to the sleeve 17, the screw 20 having axial sliding movement relative to the sleeve, but being at all times rotatable with the sleeve. Keyed at 24 to the sleeve 17 is a lock member 25 having formed externally thereon lock teeth 26 (see also Fig. 6). Cooperating with this lock member 25 is a toothed locking member 27 keyed at 28 to a horizontal shaft 29 suitably rotatably mounted within the casing 19. This shaft 29 has fixed thereto at its rear end an operating handle 30. From the foregoing it is evident that when the locking member 27 is in the full line position shown in Fig. 6 the sleeve 17 together with the screw 15 are free to rotate and when the locking member 27 is 35 swung laterally in one direction or the other one of its teeth engages the teeth on the lock member 25 and as a result, the sleeve and screw are held against rotation. The devices for manually rotating the sleeve 17 and the screw 21 are generally designated 31 and 32, respectively, and as they are substantially identical in construction, the description of one will suffice for both. As shown in Figs. 4 and 5, these rotating devices each comprises 40 an operating handle or lever 33 pivotally connected at 34 to the element rotated thereby and held in position by washers 35 carried by the said element, these washers engaging the sides of the lever. Fixed to a shaft 36 45 rotatably mounted on this lever is a reversible pawl 37 adapted to cooperate with ratchet teeth 38 formed on the element to be rotated. Secured to the shaft 36 is a lever 39 by means of which the position of the pawl 37 may be 50 reversed. The pawl 37 is adapted to be held in its different adjusted positions by means of a spring pressed plunger 40 carried by the lever 33.

Mounted on the truck frame 1 is a self-contained mining machine of the invertible overcutter type generally designated 41, normally slidable on its bottom on the mine bottom during the cutting operation, this machine being similar to that described in my copending application, Ser. No. 619,839, filed Feb.

19, 1923. Rigidly secured to the bottom of the machine 41 at the front and rear ends thereof are brackets or supports 42 pivotally mounted on horizontal shafts 43 extending longitudinally of the machine in the central longitudinal vertical plane thereof. These shafts 43 are supported within brackets 44 suitably rigidly secured to the transverse frame members 3. Threadedly connected within brackets 45 fixed to the bottoms of angle members 46 and abutting the bottom of the machine at the rear end of the latter are adjustable set screws 47, these set screws being disposed on each side of the longitudinal axis about which the machine is adapted to be tilted. As illustrated, the angle members 46 are rigidly secured to the transverse frame members 3 and are disposed inside of and parallel with the angle members 2. The upstanding sides of these angle members 46 are disposed closely adjacent the sides of the machine 41 as shown in Fig. 3.

As pointed out above the machine 41 is of the invertible overcutter type and comprises a body 48 housing a usual motor and feeding means including a rotatable feed sprocket 49 rotatable on a horizontal axis extending longitudinally of the machine and which is adapted to cooperate with a flexible feeding member or feed chain 50. Suitable 55 guide sheaves 51 are provided on the body 48 at each side of the feed sprocket 49 and are so arranged as to permit the reeving of the feed chain 50 relative to the feed sprocket in various manners as clearly described in my copending application mentioned above. Also driven by the motor housed within the body 48 is cutting mechanism including a cutter chain carrying cutter bar 52 pivoted on a vertical axis for swinging movement to positions lengthwise of the machine or at right angles to the machine at either side thereof. Suitable means is employed to rigidly lock the cutter bar in its different adjusted positions. The feed chain 50 is adapted to be 100 suitably connected to the cutter bar and upon rotation of the feed sprocket the bar may be 105 swung by power. The connection for the feed chain to the cutter bar and the means for locking the cutter bar are clearly described in my copending application mentioned above.

In the use of the improved mining apparatus it will be observed from Fig. 8 that the machine is mounted on a trackway arranged parallel with the coal face. Disposed parallel with the trackway and disposed between the rails thereof is a usual face conveyor designated by the letter A, the truck frame and wheeled supporting arms being 120 so arranged as to support the machine directly above the conveyor with the latter between the truck wheels. In case the track rails are uneven, that is, not at the same level, the operator may adjust the set screws 47 125

and thereby tilt the machine 41 about the pivots 43 until the cutter bar assumes a position in a substantially horizontal plane. The operator then connects the feed chain 50 to the cutter bar in a well known manner and upon rotation of the feed sprocket 49 this feed chain is drawn in and the cutter bar swung about its pivot from the position shown in Fig. 2 to the position shown in Fig. 8, thereby summing the cutter bar into the coal face. The cutter bar is thereafter rigidly locked in position at a right angle to the machine body. The feed chain 50 is then disconnected from the cutter bar and extended from the feed sprocket 49 around certain of the guide sheaves 51 forwardly longitudinally of the machine to a suitable anchor or roof jack B disposed adjacent the coal face between the latter and the trackway. The feed sprocket 49 is then again rotated by power and the machine fed bodily along the trackway relative to the feed chain to effect a longwall cut in the coal face. After the kerf has been cut in the face the coal is then shot down in a usual manner and loaded onto the face conveyor A by which it is conveyed away from the face. If it is desired to change the elevation of the machine so that the cutter bar may operate in different planes the operator first grasps the lever 30 and swings the locking member 27 to the full line position shown in Fig. 6, thereby releasing the lock member 25. The operator then grasps the operating handle 35 of the ratchet and pawl device 31 and oscillates the same, thereby rotating the sleeve 17 together with the screw 15 splined thereto. Rotation of the screw 15 causes the nuts 14 to move axially along the screw and in opposite directions relative to each other, thereby effecting swinging of the wheel carry arms 6 in opposite directions about their pivots 4 and thereby causing the machine to be raised or lowered as desired. It is therefore evident that the machine may be elevated into any positions from the position shown in Fig. 1 to the position shown in Fig. 7 and vice versa at will. It is evident that the screw 15 may be rotated in the opposite direction upon reversal of the position of the pawl. If it is desired to vary the angle of the machine, that is to tilt the machine about a substantially transverse axis, the operator swings the locking member 27 into the dotted line position shown in Fig. 6, thereby preventing rotation of the sleeve 17. The operator then grasps the handle of the ratchet and pawl device 32 and moves the same back and forth, thereby effecting rotation of the pressure screw 21 relative to the then stationary sleeve 17. As the screw 21 abuts the rear end of the screw 15, the latter is slid axially relative to the sleeve 17 thereby effecting swinging of the wheel carrying arms relative to each other and in the same direction and as a result causing the machine to move into a position opposite to that indicated by dotted lines in Fig. 7. It is obvious if the screw 15 is permitted to move axially in the opposite direction the machine may be tilted in the opposite direction into a position similar to that indicated by dotted lines in Fig. 7. Other uses and advantages of the improved adjustable wheeled support will be clearly apparent to those skilled in this art.

While I have in this application specifically described one form which my invention may assume in practice, it will be understood that the same has been used for purposes of illustration and that the invention may be modified and embodied in various other forms without departing from its spirit or the scope of the appended claims.

What I claim as new and desire to secure by Letters Patent is:

1. In a mining apparatus, a body supporting kerf cutting mechanism, and adjustable supporting means for said body comprising oppositely extending pivoted front and rear wheel carrying arms, means for swinging said arms comprising a screw having reversely threaded portions, reversely threaded nuts cooperating with said threaded portions, links connecting said nuts and arms, and means for rotating said screw to effect simultaneous axial movement of said nuts in opposite directions to cause swinging movement of said arms towards or away from one another to vary the elevation of said body.
2. In a mining apparatus, a body supporting kerf cutting mechanism, and adjustably supporting means for said body comprising oppositely extending pivoted front and rear wheel carrying arms, means for swinging said arms comprising an axially movable screw having reversely threaded portions, reversely threaded nuts engaging the threaded portions on said screw, links connecting said nuts and arms, and means for moving said screw axially to effect simultaneous axial movement of said nuts in the same direction to cause swinging movement of said arms in the same direction to tilt said body.
3. In a mining apparatus, a body supporting kerf cutting mechanism, and an adjustable wheeled support for said body comprising oppositely extending pivoted front and rear wheel carrying arms, said arms being pivoted between their ends and carrying wheels at one side of their pivots, means for swinging said arms connected to the latter at the other sides of their pivots from the wheels comprising a rotatable screw having reversely threaded portions, reversely threaded nuts engaging the threaded portions on said screw, links connecting said nuts and arms, and means for rotating said screw to effect simultaneous axial

movement of said nuts in opposite directions to cause swinging movement of said arms towards or away from one another to vary the elevation of said body.

5. In a mining apparatus, a body supporting kerf cutting mechanism, and an adjustable wheeled support for said body comprising oppositely extending pivoted front and rear wheel carrying arms, said arms being 10 pivoted between their ends and carrying wheels at one side of their pivots, means for swinging said arms connected to the latter at the other sides of their pivots from the wheels comprising an axially movable screw 15 having reversely threaded portions, reversely threaded nuts engaging the threaded portions of said screw, links connecting said nuts and arms, and means for moving said screw axially to effect simultaneous axial 20 movement of said nuts in the same direction to cause swinging movement of said arms in the same direction to tilt said body.

5. In a mining apparatus, a body supporting kerf cutting mechanism, and adjustable 25 supporting means for said body comprising oppositely extending pivoted front and rear wheel carrying arms, means for swinging said arms comprising a rotatable screw, oppositely movable nuts threadedly connected 30 to said screw, links connecting said nuts and arms, and means for rotating said screw to effect simultaneous axial movement of said nuts in opposite directions to cause swinging movement of said arms in opposite directions 35 to elevate said body.

6. In a mining apparatus, a body supporting kerf cutting mechanism, and adjustable supporting means for said body comprising oppositely extending pivoted front and rear 40 wheel carrying arms, means for swinging said arms comprising an axially movable screw, relatively movable nuts threadedly engaging said screw, links connecting said nuts and arms, and means for moving said screw axially to effect simultaneous axial 45 movement of said nuts in the same direction to cause swinging movement of said arms in the same direction to tilt said body.

7. In a mining apparatus, a body supporting kerf cutting mechanism, and adjustable supporting means for said body comprising oppositely extending pivoted front and rear supporting arms, means for swinging said arms comprising an axially movable 55 screw, relatively movable nuts threadedly engaging said screw, links connecting said nuts and arms, and means for moving said screw axially to effect simultaneous axial 60 movement of said nuts in the same direction to cause said arms to swing in the same direction to tilt said body, said screw moving means including a pressure screw arranged coaxially with and engaging said first mentioned screw.

8. In a mining apparatus, a body supporting kerf cutting mechanism, and adjustable supporting means for said body comprising oppositely extending pivoted front and rear supporting arms, means for swinging said arms comprising a screw, oppositely movable nuts threadedly connected to said screw, connections between said nuts and arms, means for rotating said screw to effect opposite movement of said nuts to 70 effect movement of said arms in opposite directions to change the elevation of said body without tilting the latter, and means for moving said screw axially to effect simultaneous movement of said nuts in the same 75 direction to effect movement of said arms in the same direction to tilt said body.

9. In a mining apparatus, a body supporting kerf cutting mechanism, and an adjustable wheeled support for said body comprising oppositely extending pivoted front and rear wheel carrying arms, and means connected to said arms at the opposite sides of their pivots from the wheels comprising a rotatable screw, oppositely movable nuts 80 threadedly connected to said screw, links connecting said nuts and arms, and means for rotating said screw to effect simultaneous axial movement of said nuts in opposite 85 directions to cause said arms to swing in the same direction to elevate said body.

10. In a mining apparatus, a body supporting kerf cutting mechanism, and an adjustable wheeled support for said body comprising pivoted front and rear wheel carrying arms, and means engaging said arms at the opposite sides of their pivots from the wheels for swinging the same comprising an axially movable screw, nuts threadedly connected to said screw, links connecting said nuts and arms, and means for moving said screw axially to effect simultaneous axial 90 movement of said nuts in the same direction to cause swinging movement of said arms in the same direction to tilt said body.

11. In a mining apparatus, a body supporting kerf cutting mechanism, and an adjustable wheeled support for said body comprising pivoted front and rear wheel carrying arms, and means engaging said arms at the opposite sides of their pivots from the wheels for swinging the same comprising an axially movable screw, nuts threadedly connected to said screw, links connecting said nuts and arms, and means arranged coaxially 115 with said screw for moving the same axially to effect simultaneous axial movement of said nuts in the same direction to cause swinging movement of said arms in the same direction to tilt said body.

12. In a mining apparatus, a self-contained mining machine of the type normally slideable on its own bottom on the mine bottom during the cutting operation, a frame supporting said machine, means carried by said 120 125 130

frame for tilting said machine about its longitudinal axis, and means connected to said frame for bodily elevating said machine.

13. In a mining apparatus, a self-contained mining machine of the type normally slideable on its own bottom on the mine bottom during the cutting operation, a frame supporting said machine, means carried by said frame for adjusting said machine about a longitudinal axis including a pivotal mounting for said machine, and adjustable supporting means for said frame comprising oppositely extending pivoted supporting arms, means for swinging said arms comprising a screw, oppositely movable nuts threadedly connected to said screw, links connecting said nuts and arms, and means for rotating said screw to effect simultaneous axial movement of said nuts in opposite directions to cause swinging of said arms in opposite directions to vary the elevation of said machine.

14. In a mining apparatus, a self-contained mining machine of the type normally slideable on its own bottom on the mine bottom during the cutting operation, a support for said machine, means carried by said support for tilting said machine about a longitudinal axis including a pivotal mounting for said machine, and adjustable supporting means for said support comprising oppositely extending pivoted supporting arms, means for swinging said arms comprising an axially movable screw, nuts threadedly connected to said screw, links connecting said nuts and arms, and means for moving said screw axially to effect simultaneous axial movement of said nuts in the same direction to cause said arms to swing in the same direction to tilt said machine.

15. In a mining apparatus, a self-contained mining machine of the type normally slideable on its own bottom on the mine bottom during the cutting operation, a support for said machine, means between said support and machine for tilting the latter about a longitudinal axis including a pivotal mounting for said machine, and adjustable supporting means for said support comprising oppositely extending pivoted wheel carrying arms, means for swinging said arms comprising a rotatable screw, oppositely movable nuts threadedly connected to said screw, links connecting said nuts with said arms at the opposite sides of the pivots of the latter from the truck wheels, and means for rotating said screw to effect simultaneous axial movement of said nuts in opposite directions to cause swinging of said arms in opposite directions to elevate said machine.

16. In a mining apparatus, a self-contained mining machine of the type normally slideable on its own bottom on the mine bottom during the cutting operation, and adjustable supporting means for said machine

whereby the elevation of the latter may be varied comprising oppositely extending pivoted supporting arms, means for swinging said arms comprising a rotatable screw, nuts threadedly connected to said screw, links connecting said nuts and arms and respectively pivotally connected thereto, and means for rotating said screw to effect simultaneous axial movement of said nuts in opposite directions to move said links angularly to cause swinging of said arms in opposite directions to vary the elevation of said machine.

17. In a mining apparatus, a self-contained mining machine of the type normally slideable on its own bottom on the mine bottom during the cutting operation, and adjustable supporting means for said machine whereby the elevation of the latter may be varied comprising oppositely extending pivoted supporting arms, means for swinging said arms comprising an axially movable screw, nuts threadedly connected to said screw, links connecting said nuts and arms, and means for moving said screw axially to effect axial movement of said nuts in the same direction to cause said arms to swing in the same direction to tilt said machine.

18. In a mining apparatus, a self-contained mining machine of the type normally slideable on its own bottom on the mine bottom during the cutting operation, and an adjustable wheeled support for said machine whereby the elevation and angle of the latter may be varied comprising oppositely extending pivoted wheel carrying supporting arms, means for swinging said arms comprising a reciprocable and rotatable screw, oppositely movable nuts threadedly connected to said screw, links connecting said nuts and arms, and means for rotating said screw and for moving the latter axially, rotation of said screw effecting bodily movement of said nuts in opposite directions to vary the elevation of said machine and axial movement of said screw causing bodily movement of said nuts in the same direction to swing said arms in the same direction to tilt said machine.

19. In a mining apparatus, a body supporting kerf cutting mechanism, and adjustable supporting means for said body comprising pivoted front and rear supporting arms, and means for effecting swinging movement of said arms comprising a screw, nuts threadedly connected thereto and respectively connected to said arms, means for rotating said screw to effect movement of said nuts in opposite directions to vary the elevation of said body without tilting the latter, and means for moving said screw axially to effect simultaneous movement of said nuts in the same direction to effect tilting of said body.

20. In a mining apparatus, a body supporting kerf cutting mechanism, and adjust-

able supporting means for said body comprising pivoted front and rear supporting arms and means for effecting swinging movement of said arms comprising a screw having reversely threaded portions, reversely threaded nuts cooperating with said portions respectively and connected to said arms, means for effecting rotation of said screw to effect movement of said nuts in opposite directions to change the elevation of said body without tilting the latter, and means for effecting axial movement of said screw to effect simultaneous movement of said nuts in the same direction to effect tilting movement of said body.

21. In a mining apparatus, a body supporting kerf cutting mechanism, and adjustable supporting means for said body comprising pivoted front and rear supporting arms having wheels at one side of their pivots, and means for effecting swinging movement of said arms comprising a screw, nuts threadedly connected thereto and respectively connected to said arms at the other side of their pivots from said wheels, means for rotating said screw to effect movement of said nuts in opposite directions to change the elevation of said body without tilting the latter, and means for moving said screws axially to effect simultaneous movement of said nuts in the same direction to effect tilting of said body.

22. In a mining apparatus, a body supporting kerf cutting mechanism, and adjustable supporting means for said body comprising pivoted front and rear supporting arms carrying wheels at one side of their pivots, and means for effecting swinging movement of said arms comprising a screw having reversely threaded portions, reversely threaded nuts cooperating with said portions respectively and connected to said arms at the other side of their pivots from said wheels, means for effecting rotation of said screw to effect movement of said nuts in opposite directions to swing said arms in opposite directions to change the elevation of said body without tilting the latter, and means for effecting axial movement of said screw to effect simultaneous movement of said nuts in the same direction to swing said arms in the same direction to effect tilting movement of said body.

23. In a mining apparatus, a self-contained mining machine of the type normally slidable on its own bottom on the mine bottom during cutting, a frame supporting said machine and on which the latter is pivotally mounted to rock about a longitudinal axis, and adjustable supporting means for said frame for varying the elevation and angle of said machine.

24. In a mining apparatus, a self-contained mining machine of the type normally slidable on its own bottom on the mine bottom during cutting and having cutting and feed-

ing mechanisms, a frame supporting said machine and on which the latter is pivotally mounted to rock about a longitudinal axis, and adjustable supporting means for said frame for bodily adjusting the latter to vary the elevation of said machine.

25. In a mining apparatus, a body supporting kerf cutting mechanism, and adjustable supporting means for said body including oppositely extending pivoted front and rear wheel carrying arms, and means for adjusting said supporting means including mechanism for swinging said arms simultaneously in opposite directions to vary the elevation of said body without tilting the latter and for adjusting said arms simultaneously in the same direction to tilt said body about a transverse axis.

26. In a mining apparatus, a body supporting kerf cutting mechanism, and adjustable supporting means for said body including adjustable front and rear supports, and mechanism for adjusting said supports simultaneously in opposite directions to vary the elevation of said body without tilting the latter and for adjusting said supports simultaneously in the same direction to vary the angle of said body relative to the horizontal.

27. In a mining apparatus, a self-contained mining machine of the type normally slidable on its own bottom on the mine bottom during cutting, a frame supporting said machine and on which the latter is pivotally mounted to rock about a longitudinal axis, and adjustable supporting means for said frame including adjustable front and rear supports, and mechanism for adjusting said supports simultaneously in opposite directions to vary the elevation of said frame and for adjusting said supports simultaneously in the same direction to vary the angle of said frame relative to the horizontal.

28. In a mining apparatus, a body supporting kerf cutting mechanism, and adjustable supporting means for supporting said body and for varying the elevation thereof comprising spaced oppositely extending front and rear arms pivoted between their ends and having wheels at one side of their pivots, and adjusting means for effecting simultaneous swinging movement of said arms in opposite directions including a mechanical connection extending between said arms and movably connected to all of said arms at the other side of their pivots.

29. In a mining apparatus, a body supporting kerf cutting mechanism, and adjustable supporting means for supporting said body and varying the elevation thereof comprising spaced oppositely extending front and rear arms pivoted between their ends and having wheels at one side of their pivots, and adjusting means including a mechanical connection extending between said arms and movably connected to said arms at the other side of

- their pivots for effecting swinging movement of said arms simultaneously in opposite directions to vary the elevation of said body and for swinging said arms simultaneously in the same direction to tilt said body about a transverse axis. 5
30. In a mining apparatus, a body supporting kerf cutting mechanism, and adjustable supporting means for supporting said body and for varying the elevation thereof comprising spaced front and rear oppositely extending arms pivoted between their ends at opposite sides of said body, and adjusting means mounted on said body for effecting swinging movement of said arms simultaneously in opposite directions including a single mechanical connection extending between said arms and operatively connected thereto at the other side of their pivots. 10
31. In a mining apparatus, a body supporting kerf cutting mechanism, and adjustable supporting means for said body including spaced front and rear oppositely extending arms pivoted between their ends at opposite sides of said body, and adjusting means mounted on said body including a mechanical connection extending between said arms at the other side of their pivots for effecting swinging movement of said arms simultaneously in opposite directions to vary the elevation of said body and for swinging said arms simultaneously in the same direction to effect tilting movement of said body about a transverse axis. 15
32. In a mining apparatus, a body supporting kerf cutting mechanism, and vertically adjustable supporting means for said body comprising spaced front and rear arms pivoted between their ends and having wheels at one side of their pivots, aligned rotatable screw means mounted on said body and operatively connected to and extending between said arms at the other side of their pivots, and means for rotating said screw means to effect swinging movement of said arms simultaneously in opposite directions to vary the elevation of said body and for adjusting said screw means axially to effect swinging movement of said arms simultaneously in the same direction to effect tilting movement of said body about a transverse axis. 20
33. In a mining apparatus, a self-contained mining machine of the type normally slidable on its own bottom on the mine bottom during the cutting operation, a frame supporting said machine, means carried by said frame for tilting said machine about its longitudinal axis, and adjustable supporting means on which said frame is mounted for bodily elevating said frame to position said machine at different elevations. 25
34. In a mining apparatus, a self-contained mining machine of the longwall type normally slidable on its own bottom on the mine bottom during the cutting operation
- and including a pivoted kerf cutter, a frame supporting said machine, a pivotal mounting on said frame for said machine, means carried by said frame for tilting said machine on its pivotal mounting about its longitudinal axis, means connected to said frame for bodily elevating said machine, and means for swinging said kerf cutter about its pivot relative to said frame in any elevated position of the machine. 70
35. In a mining apparatus, a self-contained mining machine of the longwall type normally slidable on its own bottom on the mine bottom during cutting and including a pivoted kerf cutter, a frame supporting said machine and on which the latter is pivotally mounted to rock about a longitudinal axis, adjustable supporting means for said frame for varying the elevation and angle of said machine, and means for swinging said kerf cutter about its pivot relative to said frame in any adjusted position of said machine. 75
36. In a mining apparatus, a self-contained mining machine of the longwall type having cutting and feeding mechanism, said cutting mechanism including a pivoted kerf cutter, a frame supporting said machine and on which the latter is pivotally mounted to rock about a longitudinal axis, adjustable supporting means for said frame for bodily adjusting the same to vary the elevation of said machine, and means for swinging said kerf cutter about its pivot relative to said frame in any adjusted position of said machine. 80
37. In a mining machine, a machine frame, cutting mechanism carried thereby, adjustable front and rear supports for said machine frame each including support wheels adapted to run along a mine trackway, said supports making an angle with each other when said frame is supported in horizontal position upon a level trackway, and mechanism for adjusting said supports simultaneously in the same direction to effect movement of said support wheels relative to each other to vary the angle in altitude of said cutter carrying frame. 85
38. In a mining machine, a machine frame, cutting mechanism carried thereby, adjustable front and rear supports for said machine frame each including support wheels adapted to run along a mine trackway, and mechanism for adjusting said supports simultaneously in opposite directions to effect movement of said support wheels relative to each other to vary the elevation of said cutter carrying frame without tilting the latter and for adjusting said supports simultaneously in the same direction to tilt said cutter carrying frame about a transverse axis. 90
39. In a mining machine, a machine frame, cutting mechanism carried thereby, adjustable front and rear supports for said machine frame each including support wheels adapted to run along a mine trackway, and mechanism

for simultaneously adjusting said supports in opposite directions to effect movement of said support wheels relative to each other to vary the elevation of said cutter carrying frame 5 without tilting the latter and to move said supports simultaneously in the same direction to move said wheels relative to each other to tilt said cutter carrying frame about a transverse axis.

In testimony whereof I affix my signature.
MORRIS P. HOLMES.
